UNITED STATES PATENT OFFICE.

VERNA E. DAVIDSON, OF DETROIT, MICHIGAN.

BURGLAR TRAP.

Application filed October 14, 1926. Serial No. 141,481.

My invention relates to a new and useful improvement in a burglar trap adapted for mounting upon buildings, particularly banks and the like, in which large sums of money or other valuables are present so that in the event of robbery those in charge in the building may operate the mechanism whereby the escape of the robbers or bandits may be prevented, while at the same time, the occupants of the building may be shielded from harm at the hands of the robbers.

It is an object of the invention to provide particularly a door closing mechanism whereby the door of the building and a shielding door may be moved to closed position and held locked in closed position.

It is another object of the invention to provide a mechanism of this class which will be simple of structure, economical of manufacture, highly efficient in use, easily and quickly installed, and simple and positive in its operation.

Other objects will appear hereinafter.

The invention consists in the combination and arrangement of parts hereinafter described and claimed.

The invention will be best understood by a reference to the accompanying drawings which form a part of this specification and in which,

Fig. 1 is a fragmentary sectional view of a building showing the invention applied with parts broken away, parts in side elevation, and parts in section.

Fig. 2 is a fragmentary sectional view taken on substantially line 2—2 of Fig. 1.

Fig. 3 is a vertical sectional view of a window shielding mechanism.

Fig. 4 is a sectional view taken on substantially line 4—4 of Fig. 3.

Fig. 5 is a perspective view of the rockable closing arm used in the invention.

Fig. 6 is a fragmentary side elevational view taken on substantially line 6—6 of Fig. 2.

In the drawings I have illustrated the invention mounted in a building having a floor 9, a ceiling 10 and a side wall 11 in which is formed the door opening 12 and the window opening 13. A partition 14 is shown dividing the room of the building into compartments, a mouth piece 15 being mounted in the partition 14 and a slide 16 being formed for a closure for the opening 17. Projected through the partition 14 and lying parallel to and spaced below the ceiling 10 is a tube 18, projecting downwardly from which, in-

termidate its ends, is a tube 19. The tube 18 communicates at one end with a housing 20 into which extends guide tube 21, slidably positioned in which is a weight 22 connecting by a cord 23 to a cord 24 which passes over a pulley 25 mounted in the housing 20 and connected to cord 26 which passes over the pulley 27 mounted in the housing 20. A cord 26 extends through the opening 28 in the floor and around the pulley 29 engaging the pulley 30 and the pulley 31 passing upwardly through the opening 32 formed in the floor 9 and extending around the drum 33 which is suitably rotatably mounted behind the partition 14 and above the floor 9.

The cord 26 may be attached at its ends to the drum 33 so that a rotation of the drum 33 in one direction will effect a winding of the cord thereon, and a rotation of the drum in the opposite direction will effect an unwinding of the same. Secured at one end to the drum 33 so as to be wound or unwound thereon and therefrom upon rotation of the same

is a cord 34 which extends around the pulley 35 and through the tube 18 downwardly in the housing 20, and through an opening formed in the guide tube 21 so as to connect to the lower end of the weight 22. The cord 24 passes over a pulley 36 and extends downwardly in the guide tube 19 into a housing 37 which is built around the window opening 13, this housing 37 having an opening 38 formed therein. Sliding panels 39 and 40 are adapted for movement across the opening 38 so as to close this opening, the cord 24 terminating in two cords 41 and 42, each of which passes around the pulley 43. The cord 41 passes around the pulley 44 and is connected at its end to a lug 45 formed on the panel 39. The cord 42 passes around the pulley 46 and is connected at its end to a lug 47 formed on the panel 40. The panel 39

is provided with rollers 49 which engage the partition 50. The panel 40 is provided with rollers 48 which also engage the upper surface of the partition 50. Partition members 51 and 52 are formed in the housing 37 to provide a runway for rollers which are mounted on the lower ends of the panels 39 and 40. Projecting downwardly from the panel 39 is a lug 53 to which is connected one end of a cord 54 which connects to the cord 55, this cord 55 connecting to the cord 26 as shown in Fig. 1. Connected to a lug 56 extending downwardly from the panel 40 is a cord 57 which also connects to the cord

55, these cords 54 and 57 passing around the pulley 58.

Mounted in the housing 20 on a vertically extending support 59 is a shaft 60 projecting from one end of which is an arm 61. Projecting from the other end of the shaft 60 and non-parallel to the arm 61 is an arm 62, the outer end 63 of which is formed slightly enlarged and preferably longitudinal. The arm 61 is connected, as shown in Fig. 1, to the cord 26, the housing 20 being provided with a slot 64 in its side wall 65 for permitting the passage of the arm 62 exterior of the housing. A door 66 is swingably mounted on the wall 11 as a closure for the opening 12, this door 66 being provided with an abutment 67 mounted thereon. Swingably mounted is an auxiliary door 68 which is adapted to close over the door 66 to provide a further closure for the opening 12 and prevent access to the door 66 from the interior of the building. The door 68 is provided with a housing 69 open at one side, so arranged that upon a rocking of the arm 62 from the dotted position shown in Fig. 1 to the position shown in full lines in Fig. 1 to move the door 68 into closed position, the portion 63 of the arm 62 riding in engagement with the inner surface of the door and striking the lower wall 70 of the housing. The drum 33 is provided with a ratchet wheel 71 adapted to rotate with the drum, this ratchet wheel being provided with teeth for engaging the electrically operated pawl or dog 72, a spring 73 serving normally to retain this pawl or dog in engagement with the teeth of the ratchet wheel 71. Carried by the drum 33 at the opposite side thereof is a ratchet wheel 74 engaging the dog 75 which is normally in engagement with the teeth of the ratchet wheel 74, the teeth in the ratchet wheel 74 being oppositely faced from the teeth in the ratchet wheel 71 so that the pawl 75 prevents rotation of the drum in one direction and the pawl 72 prevents rotation of the drum in the opposite direction. In operation the weight 22 would normally be raised, to the elevated position shown in dotted lines in Fig. 1, this moving the arms 61 and 62 into the position shown in dotted lines, permitting the opening of the doors 68 and 67 into the position shown in Fig. 2. The cords 34 and 26 would then be wound on the drum, the dog 72 preventing an unwinding of the cords so as to retain the weight in elevated position. To release the dog 72 I have provided an electrically operated latch mechanism, the detail of structure of which is not shown as it is of a well-known type and forms no specific part of the present invention. This latch mechanism is connected by the wires 76 to a press button switch 77 so that a person behind the partition 14 may, by closing the switch 77, release the dog 72 and permit a movement of the weight 22 downwardly in the guide tube 21. Upon this movement the cords 34 and 26

will be wound on the drum so that the cord 34 will prevent an upward movement of the weight 22 in the guide tube 21, thus preventing a rocking of the arm 61 downwardly to disengage the arm 62 from the door 68. When it is desired to permit movement of the parts to normal position, the drum may be rotated by the crank 78, the operator first moving the dog 75 out of engagement with the ratchet wheel 74.

In this way I have provided a simple mechanism for closing and positively locking the auxiliary door 68 in guarded position. At the same time that the door 68 moves into closing position the panels 39 and 40 will be drawn across the opening 38 by means of the cords 54 and 57. In the reverse operation the cords 41 and 42 would move the panels to inoperative position.

While I have illustrated and described the preferred form of invention, I do not wish to limit myself to the precise form of structure shown, but desire to avail myself of such variations and modifications as may come within the scope of the appended claims.

Having thus described my invention what I claim as new and desire to secure by Letters Patent is:

1. A device of the class described adapted for use with a swingable door, comprising: a rockably mounted shaft; an arm projecting radially outwardly from one end of said shaft; an arm projecting radially outwardly from the opposite end of said shaft non-parallel to said first mentioned arm, and adapted, upon rocking of said shaft, for engaging said door, and in rocking from one position to the other, for forcing said door into closed position; means connected to the other arm for rocking said shaft; and means on said door for engaging said second mentioned arm and limiting rocking movement of said shaft in one direction beyond a predetermined degree.

2. A device of the class described adapted for use with a swingably mounted door, comprising: a rockably mounted shaft; an arm projecting radially outwardly from one end of said shaft; an arm projecting radially outwardly from the opposite end of said shaft non-parallel to said first mentioned arm; a wear plate on the face of said door; an abutment member on said wear plate, said second mentioned arm adapted, upon rocking of said shaft in one direction, for riding over said wear plate and forcing said door to closed position, the engagement of said door with said abutment member limiting rocking movement of said shaft in said direction.

3. A device of the class described adapted for use with a swingably mounted door, comprising: a rockably mounted shaft; an arm projecting radially outwardly from one end of said shaft; an arm projecting radially outwardly from the opposite end of said shaft

non-parallel to said first mentioned arm; a wear plate on the face of said door; an abutment member on said wear plate, said second mentioned arm adapted, upon rocking of said shaft in one direction, for riding over said wear plate and forcing said door to closed position, the engagement of said door with said abutment member limiting rocking move-

ment of said shaft in said direction; a flexible member secured to said first mentioned arm; and a weight for moving said flexible member and rocking said shaft in one direction. 10

In testimony whereof I have signed the foregoing.

VERNA E. DAVIDSON.
